UNITED STATES PATENT OFFICE

ARTHUR HERMAN ADAMS, OF YONKERS, NEW YORK, ASSIGNOR TO WESTERN ELECTRIC COMPANY, INCORPORATED, OF NEW YORK, N. Y., A CORPORATION OF NEW YORK

APPARATUS FOR TREATING OBJECTS

Original application filed November 19, 1927, Serial No. 234,361. Divided and this application filed November 24, 1928. Serial No. 321,622.

This invention relates to apparatus for treating objects, and more particularly to apparatus for applying coating material to objects.

5 The object of this invention is to provide an improved apparatus for treating objects in an expeditious and economical manner to provide a smooth, uniform coating, and is a division of my co-pending application, 10 Serial No. 234,361, filed November 19, 1927.

In accordance with the general features of this invention there is provided in one embodiment thereof a freely rotatable basket containing loosely arranged objects to be 15 coated, which is designed to be immersed in a bath of molten tin, zinc, alloy, wax, pitch, or other coating material. The bath, which may be tin, is contained in a rotatable receptacle provided with an enlarged portion.

20 When the receptacle is rotated, motion is also imparted to the perforated basket through the bath of molten tin, and when a certain speed is attained the major part of the tin is gradually thrown outwardly, due 25 to the action of centrifugal force as speed is acquired and collects in the enlarged portion of the receptacle, leaving the perforated basket entirely free of the bath of tin.

During this stage of the operation the bath 30 of molten tin gradually recedes from the objects in the basket, removing as it recedes all excess tin by the combined effect of the surface tension of the bath of tin and of centrifugal and gravitational forces, thereby 35 resulting in a smooth and uniform coating. The effect is the same as though a basket of objects was withdrawn from a bath of tin in a much greater gravitational field than the earth affords.

40 Other objects and advantages of this invention will more fully appear from the following detail description taken in connection with the accompanying drawing, in which

45 Fig. 1 is a fragmentary plan view of an apparatus embodying the features of this invention;

Fig. 2 is a vertical section, partly in elevation, taken on the line 2-2 of Fig. 1, and

50 Fig. 3 is a fragmentary detail section

through the vertical axis of the basket which holds the objects.

Referring now to the drawing in detail wherein like reference numerals indicate similar parts, and particularly to Fig. 2, a 55 circular base 10 rotatably supports by means of suitable anti-friction bearings a circular receptacle 11. Attached to a lower reduced bearing portion of the receptacle 11 is a worm gear 12 which meshes with a worm 13 which may be driven from a suitable source of power (not shown). The receptacle 11 is provided with an enlarged portion 14 at its upper end, the purpose of which will become apparent as this description progresses, the portion 14 having an axial opening 15 at its top surface.

Coaxially arranged with and rigidly supported above the receptacle 11 is a non-rotatable shaft 18 which is adapted to be reciprocated in a vertical direction by any suitable means (not shown). Rotatably mounted upon the lower end of the shaft 18 by suitable anti-friction bearings is a sleeve 19, a head 20 of the shaft holding the sleeve 70 thereon. The sleeve 19 is provided in the present instance with three outwardly and downwardly extending arms or spiders 21. Suspended from the free ends of the spiders 21 is a circular basket 23 formed of sheet 75 metal having its vertical and lower walls perforated, the whole being strengthened by a plurality of metal bands 24, the upper ends of which extend above the top edge of the basket and above a normal immersion level 25 of the molten tin or other coating material. The free ends of the spiders 21 are attached to the upper ends of the bands 24 by suitable readily releasable means. The sleeve 19 is of such a length that taken 80 with the three spiders 21, the basket 23 is maintained sufficiently rigid upon the shaft 18 in the operation of the apparatus that no appreciable lateral movement of the basket within the receptacle 11 occurs. The 85 receptacle 11 is provided with a plurality of circularly and uniformly arranged ribs 26 extending from its inner peripheral wall toward the axis thereof and spaced from the peripheral surface of the basket 23 suf-

ficiently to not interfere with its free rotation. In addition to one purpose of the ribs 26 which will be described hereinafter in the description of operation of the apparatus, they also serve as a means to steady the basket 23 during its rotation and facilitate the guiding thereof through the opening 15 of the receptacle, and into the ring guard 33 when it is being withdrawn from the 10 receptacle.

Removably attached at its lower end to the basket 23 within an opening formed axially in the lower perforated wall thereof is an imperforate wall tube 27, the opening 15 in its lower end having a screen or sieve 28. The tube 27 is removably secured in position in the basket 23 by inserting the lower end thereof in a sleeve 29 (Fig. 3) fixed to the bottom wall of the basket within the axial 20 opening thereof. The upper end of the tube 27 is flared and lies flush with the upper edge of the basket 23. The purpose of the tube 27 in the operation of the apparatus serves as a depository for dross or 25 other foreign matter contained in the bath, which in the centrifuging action is attracted to the axis of the rotating parts by the vortex created and flows into the flared mouth of the tube and is retained at the bottom 30 thereof by the sieve 28, any molten metal passing therethrough.

Surrounding the lower reduced portion of the receptacle 11 is an oven 30 provided with a plurality of nozzles 31 for projecting 35 against the sides of the receptacle gas flames to maintain the tin and the objects to be coated at a sufficiently high temperature to facilitate the flow of the metal around the objects to thoroughly envelop them and in 40 the centrifuging action the removal of all excess metal therefrom. Attached to the walls of the oven 30 and surrounding the enlarged portion 14 of the rotatable receptacle 11 is a housing or guard 32 provided at 45 its upper end with a collar portion 33, the diameter of which is sufficiently large to receive the basket 23 when it is raised from the receptacle 11 during the centrifuging operation to be described shortly herein- 50 after. The portion 33 serves to prevent the scattering of molten metal particles into the space above the top of the guard 32 with the likelihood of injury to an operator as the rotating basket is raised from the receptacle 11. Substantially one-half of the portion 33 may be swung open about a hinge 55 34 to permit the basket 23 to be moved from the apparatus to another position. To permit this the reciprocable shaft 18 with the attached basket 23 together with the means for reciprocating it may be swung to one side upon being drawn upwardly to the dotted line position, the basket detached 60 65 therefrom, another basket attached thereto

and then swung back into axial alignment with the receptacle 11.

Upon the rotating basket 23 reaching the dotted line position thereof a circular brake surface 37 formed upon the upper end of the sleeve 19 engages a suitably supported stationary friction member 38. The member 38 is ring shaped but cut open on one side to permit the shaft 18 with the basket 23 to be swung to one side as described hereinbefore. Thus the basket 23 is quickly brought to a stop upon reaching its upper position.

In practicing a method of metal coating small objects with the hereinbefore described apparatus the bath of tin contained in the receptacle 11 is brought to a suitable temperature in the manner and for the purpose hereinbefore described. The bath of tin is then skimmed of any surface impurities and the basket 23 with the objects therein is lowered into the bath and when the basket has been completely submerged the receptacle 11 is caused to rotate. The speed of rotation of the receptacle 11 may be increased very rapidly by the normal acceleration of a motor or belt driving it through the worm 13. The bath of tin will accelerate more gradually, due to its friction on the walls of the receptacle 11. The ribs 26 of the receptacle 11 it will be apparent serve to facilitate the rotation of the bath of tin around the basket 23 and thus the latter is caused to rotate with it. In fact, the bath cannot rotate much more rapidly than the basket, due to the surface friction created between the mass of tin, the basket and the mass of objects therein. As the velocity of the bath and basket increases the centre of the bath collects the lighter or surface slag and impurities and the crater of the surface is finally lowered sufficiently to be intersected by the flaring top edge of the tube 27, thus segregating these impurities so they cannot descend with the clean metal and be deposited on the objects in the basket. Just after this occurs, and not before, the level of the tin reaches the height of the objects in the basket 23, it is well to further cleanse the surface of the bath by sprinkling it with a flux, such as rosin, tallow, any very high flash paint oil, or with dry zinc chloride or ammonium chloride. The specified fluxes are particularly adapted for use with baths of tin and when other baths are employed suitable fluxes therefor should be selected. The impurities will be intercepted by the tube 27 and confined within that tube until the central level of the bath is lowered to a point just below the screen 28, where all but the finest of the slag and impurities will be deposited. The tube 27 as hereinbefore described is removable so that the slag and impurities may be readily removed therefrom and the screen 28 cleaned. The 130

- screen 28 is preferably cleaned at the end of each cycle of operation, just before fresh objects to be treated are put in the basket 23. In the meanwhile, as the surface of the bath takes the well known form of a paraboloid of revolution of increasingly sharp curvature, indicated by the broken line 39, the tin overflows progressively past the knee or corner 40 of the receptacle 11, into the upper and outer enlarged portion 14 thereof. Obviously as this process continues the bath flows very gradually away from the basket and the therein contained objects, its surface moving through them both downwardly and outwardly, forming in the lower part of the receptacle 11 successively paraboloids of revolution. It will be noted that each drop of tin on any object near the surface of the bath is pulled in a direction normal to that surface by the resultant of centrifugal and gravitational forces. It will be noted that the surface tension of this receding surface is also in this same direction. The method and apparatus of the present invention is particularly useful in that the last drop on any outward edge or corner of an object, which is very hard to throw off and which is likely either to remain or make a lump when cold or dry, or to fly off and spatter up others of the mass of objects is removed due to the additive stripping effect of gravity, centrifugal force and surface tension. Also since it is not necessary to remove the objects from the effects of the hot bath, additional heat is not required to keep the metal or material on their surface uniformly hot and free flowing and the formation of oxides and slags is thereby prevented.
- It will be clear that, as soon as the bath has attained the speed of the receptacle 11, which can be determined in a number of ways, as by the power consumption going down, cessation of power loss in fluid friction, or by a simple observation through the top opening by a mirror, or more practically by noting once and for all the time it takes, there is no further advantage in continuing to revolve the basket 23, but rather a danger of cooling the parts and of sticking them together. The basket then should be raised to the position shown in dotted lines inside of guard ring 33, and its rotation should be stopped as quickly as possible, which may be accomplished through the use of the brake surface 37 engaging the stationary friction member 38.
- The power should be cut off from worm 13 and the receptacle 11 allowed to come to rest. The bath therein will also come to rest and become level, which is facilitated, it will be apparent, by the ribs 26 of the receptacle 11. It may require replenishing at this time.
- The basket is removed from the spiders
- 21, dumped quickly so the objects will not stick together. The strainer 28 is cleaned, the basket is refilled, or another one already filled with objects ready for coating may be used, and replaced on the spider and then subjected to the molten bath which has been prepared in the manner previously described.
- Although this invention has been disclosed and described in connection with the coating of small objects with tin, it will be understood that the invention is capable of other applications and is only to be limited by the scope of the appended claims.
- What is claimed is:
1. In an apparatus for treating objects, a receptacle containing treating material, a receptacle for immersing objects to be treated in the treating material, and means for effecting relative movement between the treating material and the receptacle containing the objects immersed therein resulting in the formation of a hollow in the treating material free from the objects and the removal of the excess treating material from the objects.
  2. In an apparatus for treating objects, a rotatable receptacle containing treating material, means for immersing the objects to be treated in the treating material, and means for rotating the receptacle to cause a centrifuging of the treating material free from the objects.
  3. In an apparatus for applying coating material to objects, a rotatable receptacle containing coating material, means for immersing the objects to be treated in the material, means for rotating the receptacle to cause a centrifuging of the residual material free from the objects, and means for withdrawing the coated objects from their normal immersion level in the receptacle.
  4. In an apparatus for applying coating material to objects, a rotatable receptacle containing coating material, a perforated basket for holding the objects to be coated, a reciprocal member from which the basket is suspended for causing an immersion of the basket in the coating material, the receptacle, the basket and the member being in coaxial alignment, and means for rotating the receptacle to cause a centrifuging of the residual material free from the basket and the objects therein.
  5. In an apparatus for applying coating material to objects, a rotatable receptacle containing coating material and having an enlarged diameter at its upper end, a perforated basket for holding the objects to be coated, a reciprocal member upon which the basket is rotatably suspended for causing an immersion of the basket in the coating material, the receptacle, the basket and the member being in coaxial alignment, and

means for rotating the receptacle to cause a centrifuging of the residual material free from the basket and the objects therein into the enlarged portion of the receptacle and 5 a rotation of the basket upon the reciprocal member.

6. In an apparatus for applying coating material to objects, a rotatable receptacle containing coating material, means for immersing the objects to be coated in the material, means for rotating the receptacle to cause a centrifuging of the residual material free from the coated objects, and means carried by the object immersing means 10 for establishing a passage for dross in the coating material, such dross being directed thereto by the vortex created during the centrifuging action.

7. In an apparatus for applying a metallic coating to objects, a rotatable receptacle containing a molten metal means for immersing the objects to be coated in the material and withdrawing them from the receptacle, said latter means including a 20 perforated basket disposed in axial alignment with the receptacle, means for maintaining the metal in a molten state, means for rotating the receptacle to cause a centrifuging of the residual coating free from the basket and the coated objects, and an imperforate wall tube carried coaxially in the basket, and open upper end of the tube disposed substantially at the normal level of the molten metal and its lower end within 25 30 an opening in the receptacle and provided with a perforated wall thereacross.

In witness whereof, I hereunto subscribe my name this 14th day of November, A. D., 1928.

40 ARTHUR HERMAN ADAMS.
